UNITED STATES PATENT OFFICE.

SYLVANUS HUSSEY, OF GOWANDA, NEW YORK.

ROCK-DRILL.

SPECIFICATION forming part of Letters Patent No. 244,608, dated July 19, 1881.

Application filed December 4, 1880. (No model.)

To all whom it may concern:

Be it known that I, SYLVANUS HUSSEY, of Gowanda, in the county of Cattaraugus and State of New York, have invented new and useful Improvements in Rock-Drills, of which the following is a specification, reference being had to the accompanying drawings.

This invention relates more particularly to a rock-drill for which Letters Patent of the United States No. 232,609 were granted to me September 28, 1880, to which reference is here made for a full description thereof.

The object of my present improvements is to increase the adjustability and improve the operation of the drill; and it consists, first, of the mechanism whereby the feed is given to the drill-bar; second, in the particular construction of the device whereby the drill-bar is raised and lowered; third, in the construction of the device whereby the drill-bar is clamped during its upward and downward movement; fourth, in constructing the mechanism whereby the drill-bar is raised with an extensible lower portion, whereby the range of movement of the drill-bar can be adjusted; fifth, of the particular construction of this extensible portion of the elevating mechanism; seventh, in providing the lower end of the swinging drill-frame with an adjustable foot, whereby the same can be steadied; and, finally, of the particular construction of this adjustable foot, as will be hereinafter fully set forth.

In the accompanying drawings, consisting of two sheets, Figure 1 is a side elevation, Fig. 2 a sectional elevation, and Fig. 3 a front elevation, of a rock-drill provided with my improvements. Fig. 4 is a vertical section of the gripping mechanism, whereby the drill-rod is operated. Fig. 5 is a horizontal section in line $x x$, Fig. 4. Fig. 6 is a vertical section of the movable frame, which carries the eccentric clamps in line $z z$, Fig. 7. Fig. 7 is a perspective view of the movable frame. Fig. 8 is a vertical section, on an enlarged scale, of a portion of the adjustable foot of the swinging frame. Fig. 9 is a horizontal section in line $w w$, Fig. 8. Fig. 10 is a section, on an enlarged scale, through one of the segments in which the movable frame is adjusted.

Like letters of reference refer to like parts in the several figures.

A represents the tripod-base; B, the main

frame connected to the base by a vertical pivot-bolt, b ; and c , the swinging frame hung on the horizontal shaft c , which is journaled in bearings in the frame B in the usual manner.

D represents two segments formed with the frame B concentric with the shaft c , and E represents the rear cross-bar of the swinging frame C. The ends of the cross-bar E are provided with pins or bolts e , which project through the slot of the segment D, and are provided on the outer side of the segment with a washer, e' , and nut e'' . The segments D are provided on their outer sides with serrations, and the washer e' is provided on its inner side with corresponding serrations, so that upon tightening the screw-nut e'' the serrations of the washer will be forced into the serrations of the segment, whereby the swinging frame C is held securely in place.

F represents the drill-bar, and $f f'$ the levers by which the drill-bar is operated. The central lever, f , engages against the under side of the gripping mechanism, and serves to raise the drill-bar; and the side levers, f' , are connected by rods or links g with the upper end of the gripping mechanism, and serve to clamp the drill-bar during its downward movement.

The gripping mechanism is inclosed in a casing, $H H'$, and consists of two or more eccentrics, h , pivoted between ribs i , forming part of a frame, I, which slides loosely on the drill-bar. The ribs i are connected at their upper ends by a ring, i' , which is secured to or cast in one piece with the ribs. The eccentrics h are provided with upwardly-extending arms h' and downwardly-extending arms h'' , the latter being curved outward, as shown. The frame I rests by means of its ring i' against a shoulder, j , formed on the inner side of the lower portion, H , of the casing in which the gripping mechanism is inclosed.

K represents the lower head of the casing H, and L is a sleeve which surrounds the bar F, and which has a conical head, L' , which projects into the casing H and between the lower arms, h'' , of the eccentrics h . The head L' rests upon an offset or shoulder of the head K.

l is a spiral spring arranged in an annular recess of the head L' around the drill-bar F, and bearing with its upper end against the under side of the frame I, to which the eccentrics are attached, thereby holding the frame I

against the shoulder j and preventing it from coming in contact with the conical head L' .

The lower end of the sleeve L is provided with an external screw-thread, m , to which is applied a screw-sleeve, M , which is secured in place by a jam-nut, m' . By adjusting the screw-sleeve M on the sleeve L the length of the latter can be increased or reduced, thereby increasing or reducing the stroke of the drill-bar.

N represents the head, whereby the eccentrics h are clamped against the drill-bar during the downward movement of the latter. It is provided on its under side with a concave recess, n , which engages over the upper arms, h' , of the eccentrics, and has an annular shoulder, n' , which strikes against an overlapping flange, n^2 , on the upper end of the upper portion, H' , of the casing. The head N is attached to the links g by wrist-pins g' .

As the central lever, f , moves upward it strikes against the lower end of the sleeve L , raising the latter and forcing its conical head against the lower arms, h^2 , of the eccentrics, whereby the arms h^2 are swung outward and the eccentrics h tightened on the drill-bar. The latter is thereby raised until the lever f has completed its upward stroke. Just before the upward movement of the lever f and the drill-bar is completed the side levers, $f' f'$, are released, whereby the

head N is permitted to drop over the upper arms, h' , of the eccentrics h , thereby pressing the arms h' inward and clamping the eccentrics against the drill-bar. The sleeve L and the lever f are now released by the actuating mechanism, and the drill-bar is forced down by the reaction of the spring O , the eccentrics h clamping the drill-bar during this downward movement. The side levers, f' , begin their upward movement somewhat in advance of the

central lever, f , whereby the head N is raised and the upper arms, h' , of the eccentrics are released before the sleeve L is raised and the lower arms, h^2 , are actuated by the conical head L' . The spring l keeps the frame I in

its highest position in contact with the shoulder j , thereby leaving an open space between the lower ends of the ribs i and the lower head, K , of the casing. This open space permits the blow to be delivered with full force upon the rock, and permits the frame I to descend in the casing as the blow is delivered until the ribs i strike the bottom plate, K . As soon as the head N is raised by the upward movement of the side levers, f' , the spring l , which was com-

pressed by the downward movement of the frame I , raises the latter against the shoulder j , and thereby causes the eccentrics h to seize the drill-bar at a higher point. The distance to which the frame I is so raised constitutes the feed which the drill-bar receives at the beginning of every upward stroke.

$P P$ represent the upright bars of the swinging frame C , and Q represents an adjustable foot or rest, arranged between the lower portions of the bars $P P$ to steady the swinging frame and the lower end of the drill-bar. The

rest Q consists of a sleeve or hollow cylinder, R , secured between the lower ends of the bars $P P$, and parallel therewith, and a tube, S , sliding loosely in the sleeve R , and secured therein in any desired position by a ring, s , which is arranged in a recess in the sleeve R and surrounds the tube S . The ring s is provided with a threaded shank, s' , which projects out of the recess in the sleeve R , and which carries a screw-nut, t , bearing against the outer side of the sleeve R , so that upon tightening the nut t the ring s is drawn against the tube S , and the latter secured in place, while upon releasing the ring s the tube can be freely raised and lowered in the sleeve R .

T is a pointed rod or bar fitted loosely in the tube S , and having its lower portion provided with an external screw-thread, u , working in a screw-nut, U , attached to the lower end of the tube S by a screw-thread or otherwise. The upper end of the rod T is provided with a suitable handle for turning it. The rod T is raised and lowered by turning it in the screw-nut U , and when this adjustment is insufficient the tube S can be raised or lowered, thereby affording a large range of adjustment.

The sleeve R carries an arm, R' , which is provided with an aperture, in which the drill-bar is guided.

I claim as my invention—

1. The combination, with the drill-bar, of a casing, H , inclosing the gripping mechanism, a frame, I , which carries the gripping mechanism, and which has a limited vertical movement in the casing H , a spring, l , which tends to hold the frame I in its highest position, and mechanism whereby the gripping mechanism is released before the upward stroke of the drill-bar begins, whereby the frame I is raised in the casing and the gripping mechanism caused to seize the drill-bar at a higher point at every upward stroke of the drill-bar, substantially as set forth.

2. The combination, with the drill-bar, of the movable sleeve L , casing H , provided with shoulder j , frame I , carrying the eccentrics h , and a spring, l , interposed between the sleeve L and the frame I , substantially as set forth.

3. The combination, with the drill-bar, of the movable sleeve L , casing H , having a shoulder, j , frame I , carrying the eccentrics h , provided with arms $h' h^2$, a spring, l , interposed between the sleeve L and frame I , and the head N , having a recess, n , substantially as set forth.

4. The combination, with the drill-bar, of the clamping devices $h h$, and a sleeve, L , having its upper end constructed to close the clamping devices, and having its lower end provided with an extensible portion, M , substantially as set forth.

5. The combination, with the drill-bar, of the sleeve L , provided at its lower end with a screw-thread, m , a screw-sleeve, M , applied thereto, and a jam-nut, m' , substantially as set forth.

6. The combination, with the base A, and main frame B mounted thereon, of the drill-frame C, hung in the frame B, and adapted to swing in a vertical plane, and an adjustable foot or rest, Q, secured to the lower part of the swinging frame C, whereby the latter is supported on the ground when adjusted at various angles, substantially as set forth.

7. The combination, with the swinging drill-frame C, of an adjustable foot or rest composed

of a stationary sleeve, R, a tube, S, made adjustable in the sleeve R, and provided with a threaded portion U, and a rod or bar, T, having a screw-thread, u, engaging with the threaded portion U of the tube S, substantially as set forth.

SYLVANUS HUSSEY.
